HUGH M. STOLLER AND HUBERT A. PATTISON, OF NEW YORK, N. Y., ASSIGNEES TO
WESTERN ELECTRIC COMPANY, INCORPORATED, OF NEW YORK, N. Y., A CORPORATION
OF NEW YORK.

ELECTRIC CONTROL SYSTEM.

Application filed March 28, 1921. Serial No. 456,438.

To all whom it may concern:

Be it known that we, HUGH M. STOLLER and HUBERT A. PATTISON, citizens of the United States, residing at New York, in the county of New York, State of New York, have invented certain new and useful Improvements in Electric Control Systems, of which the following is a full, clear, concise, and exact description.

- 10 This invention relates to improvements in electric control systems for prime mover dynamo plants and more particularly to such plants employing an internal combustion engine as the prime mover.
- 15 One of the objects of the invention is the provision of an electromagnetic regulator comprising a unitary structure which serves to control the output of the generator commensurate with the demands of the supply circuit to which it is connected, to indicate the current developed thereby under various conditions, and to stop the prime mover by breaking the ignition circuit therefor, under predetermined conditions. Where a battery 25 is employed and the dynamo may also be used as a motor for starting the prime mover, the regulator, in addition to its functions just enumerated, also serves as a starting switch and as a means for preventing 30 discharge of the battery through the dynamo when the plant is stopped.

Other objects and advantages of the invention will be set forth in detail in the following specification, and particularly 35 pointed out in the appended claims.

In the accompanying drawings,

Fig. 1 is a diagrammatic view of a direct connected prime mover generator plant showing the elements of the electromagnetic regulator and their connection to the carburetor of the prime mover and to a typical circuit including a battery, ignition circuit for the prime mover, and load circuit.

Fig. 2 is a fragmentary, detail view illustrating the various positions of the operating handle and its connection with the electromagnetic regulator and with a pair of electrical contacts used in securing an overcharge of the battery when one is employed.

The construction and operation of the invention can best be understood by reference in detail to the accompanying drawing in

which 10 indicates a prime mover which is 55 illustrated as an internal combustion engine, but it is to be understood that the invention is equally applicable to other prime movers, such as steam engines, heat engines and the like, employing a fuel valve 60 for the control thereof. A generator 11 has its armature mounted on the crank shaft 12 of the engine 10, and is provided with a series field 13, and a shunt field 14 differentially wound, the latter being connected 65 directly across the brushes 15 and 16.

The electromagnetic regulator comprises a series coil 17 and shunt coil 18 wound upon a U-shaped core 19 between the opposite poles 20 of which an armature 21 is 70 rotatably mounted upon a shaft 22. A spring 23 serves to hold the armature and shaft in the positions illustrated. The lower end of the shaft 22 carries a butterfly throttle valve 24, of usual construction, located 75 within the fuel intake pipe 25 of the engine 10. An arm 26 secured to the shaft 22 has a pin and slot connection with a lever 27 secured to the upper end of a needle valve 28. When the shaft 22 is actuated, 80 as will be hereinafter explained, the butterfly valve 24 and the needle valve 28 will be actuated to simultaneously cut off or increase the fuel and air fed into the intake pipe 25, as is readily understood. The upper end of the shaft 22 is journaled within 85 a plate 29 and carries a pointer 30, which cooperates with a scale 31 formed on the plate, the purposes of which will be hereinafter explained. The shaft 22 also carries an arm 32 which is adapted to engage 90 a lever 33 mounted upon a shaft 34, journaled in the plate 29, which carries upon its upper end an operating handle 35 having a projection 36 which serves as a pointer 95 cooperating with index points 37, formed on the plate 29.

The operating handle 35 is shown in its normal position in which the lever 33 is so disposed that it is out of the path of the arm 100 32 which may be moved counter-clockwise until it engages a stop 38, the arm being normally held against a second stop 39, by the tension of the spring 23 exerted on the armature 21. A third arm 40 is fixed to the 105 shaft 22 and carries a button 41 of insulating material which is adapted to engage a contact spring to make and break the igni-

tion circuit for the prime mover and the main line or load circuit, as will be herein-after explained in detail.

The various circuit connections for the generator, the electromagnetic regulator, the ignition circuit for the internal combustion engine and the load circuit will now be explained. The brushes 15 and 16 of the generator arm connected with main conductors 50 and 51, respectively, the former adapted to be made or broken by a contact spring 52 and contact 53, and the latter connected to the series coil 17 and shunt coil 18 of the electromagnetic regulator. The primary ignition circuit comprises the primary winding 55 of an ignition coil and a timer in series therewith which is connected to a contact 56. This circuit is bridged across the main conductors 50 and 51 when the contact spring 53 is brought into engagement with the contacts 52 and 56. The secondary winding 57 of the ignition coil has one end connected to a spark plug 58 and its other end grounded at point 59 on the engine 10. A load, which is illustrated as a plurality of lamps 60, is bridged across the main conductors 50 and 51, as is also a secondary battery 61, its connection to the conductor 50 being between the load 60 and the contact springs 52 and 53, so that, though the main conductor 50 be broken by the separation of the contacts 52 and 53, the load 60 may still be supplied by current from the secondary battery 61.

In Fig. 1 the various elements of the system are illustrated in the positions that they occupy when the internal combustion engine 10 and the generator 11, driven thereby, are inactive. The contact spring 53 is out of engagement with the contacts 52 and 56, so that the main conductor 50 is broken and the primary ignition circuit open, the load 60 being supplied with current, when desired, from the secondary battery 61. When the charge in the secondary battery reaches such a low point that it cannot meet the demands of the load 60, as may be indicated either from the action of the load (such as the dimming of the lights, where they comprise the load) or by a suitable voltmeter or hydrometer (not shown), it is desirable to start up the generator to recharge the battery and also perhaps to supply the load. To do so, the operating handle 35 is turned counterclockwise from its normal position, in which the pointer 36 is opposite an index point 37 marked "Stop automatic," to the index point 37 marked "Start." This movement of the handle 35 rotates the shaft 34 counter-clockwise causing a lever 63 carried by the shaft to engage the tail 64 of a latch and move it downwardly. The said latch is pivoted at 65, and the downward movement of the tail 64 causes a latching arm 66, integral therewith, to release the contact spring

53 and permit it to spring upwardly into engagement with contacts 52 and 56. Upon the closing of contacts 52 and 53, current is supplied the generator 11 from the secondary battery 61, causing it to operate as a motor to crank the gas engine 10, the series field 13 and shunt field 14 at this time operating cumulatively to secure a high torque. As the piston is reciprocated, ignition current is supplied the spark plug 58 through the closing of contacts 52, 53 and 56, and explosive mixture is fed through the intake 25, the needle valve 28 and butterfly valve 24 being held in their wide open positions by the action of the spring 23. The explosive mixture may be varied in starting by the use of a usual form of "choke valve" (not shown), or after moving the handle 35 to a point intermediate the index points "Start" and "Stop automatic" the shaft 22 and air and gas valves operated thereby, may be adjusted manually by turning the pointer 30 attached to the said shaft. Preferably, however, the handle is kept at the "start" position and a choke valve employed.

The handle 35 is held in its adjusted position until the engine starts, which causes the generator 11 to operate as a generator, the fields 13 and 14 at this time operating differentially, and when the voltage of the generator rises sufficiently to overcome the counter electromotive force of the secondary battery 61, the current in the mains 50 and 51 reverses and current is supplied the battery and load circuit passing through the series and shunt coils of the electromagnetic regulator. These coils are differentially wound, and preferably so proportioned that the magnetic flux developed by the shunt coil is so much greater than that developed by the series coil so that when the dynamo is charging the battery, the armature 21 is controlled substantially by the shunt coil, causing it to be rotated counter-clockwise a distance commensurate with the voltage in the main conductors 50 and 51 and the counter-acting force of the spring 23. The handle 35 may now be moved from the position "start" back to the index point 37 marked "stop automatic." If the load increases, the voltage in the coil 18 will drop, reducing the flux and permitting the spring 23 to rotate the armature to open up the valves 24 and 28, causing the engine and generator to speed up and take care of the increased load. As the load decreases the opposite action will take place, the voltage in the coil 18 rising, increasing the flux and causing the armature 21 to turn the shaft 22 to further close the valves 24 and 28, reducing the speed of the engine and the output of the generator.

In order to secure the desired movement of the armature 21 without too great change in the voltage of the system, the air gap

between the armature and the pole pieces 20 is tapered so that it diminishes as the armature is rotated clockwise. As the armature oscillates back and forth, due to the varying voltage in the coil 18, the hand 30, carried by the shaft 22, passes over the index 31 which is so calibrated as to indicate the approximate current output of the generator.

10 As long as there is no load connected to the mains 50 and 51 and the secondary battery 61 is not fully charged, the engine will continue to operate and drive the generator 11. When the load is cut out of the line 15 and the secondary battery 61 approaches a fully charged condition, the voltage of the coil 18 becomes higher causing the armature 21 to bring the arm 40 nearer the contact spring 53. When the secondary battery 20 61 is fully charged, the arm 40 will have been moved a distance sufficient to depress the contact spring and snap it under the latching arm 64 which is held in normal latching position by a spring 67. As soon 25 as the contact spring 53 is moved out of engagement with the contacts 52 and 56, the line circuit will be broken and the ignition circuit interrupted causing the engine to stop. The breaking of the line circuit 30 interrupts the circuit for the coils 17 and 18 of the electromagnetic governor permitting the spring 23 to rotate the armature 21 and shaft 22 to open up the valves 24 and 28 ready for the next starting operation.

To keep a secondary battery in the most efficient condition, and also to increase its life, it is found necessary to periodically give it what is termed an "overcharge," the 40 reasons for which are well known by those skilled in the art. In order to give the secondary battery 61 an overcharge in the system illustrated, the magnetic flux of the shunt coil 18 is so reduced that the series 45 coil and spring 23 are permitted to rotate the armature 21 into the position illustrated in which the valves 24 and 28 are wide open. The current passing through the shunt coil 18 from the main 51 normally 50 flows through conductors 68, 69, normally closed contact springs 70 and 71, and conductors 72 and 73 to the main 50, short circuiting a resistance 74 connected between the junction of conductors 68 and 69 and conductors 72 and 73. When it is desired 55 to overcharge the battery, the operating handle is moved clockwise until the pointer 36 comes opposite the index point marked "overcharge." This movement of the handle 60 35 rotates the arm 33 clockwise a distance sufficient to move a button 75, carried thereby, against the contact spring 71 and separate it from contact with the contact spring 70. The separation of contact springs 70 and 71 breaks the short circuit around re-

sistance 74 and introduces it into circuit with the shunt coil 18. The resistance 74 so cuts down the flux of the shunt coil 18 that the spring 23 is permitted to hold the armature 21 and the valves 24 and 28 in the positions shown.

During the charging of the battery, should the current in the charging circuit reverse and tend to discharge the battery through the generator, a means is provided which 75 serves under such conditions to break the charging circuit and also the ignition circuit, thereby stopping the engine. This means comprises the series and shunt coils of the electromagnetic regulator. As was previously explained during the charging of the battery, the series coil 17 opposes the shunt coil 18, but the latter is so much stronger than the former that the shunt coil virtually controls the movement of the armature 21. 80 However, should a heavy reversal of current occur in the charging circuit due to the stopping of the engine through exhaustion of the fuel, failure of the ignition circuit or other causes, the current flowing through the series 85 coil would be in a reverse direction so that its flux would be added to the flux developed by the shunt coil, and the resultant flux would be sufficient to rotate the armature 21 counter-clockwise against the tension of the 90 spring 23 and lock up the spring contact 53 through the medium of arm 40, thereby breaking the main line circuit at the contact 95 52 and the ignition circuit at the contact 56.

Although the electromagnetic regulator is 100 illustrated and has been described as applied to a prime mover dynamo plant employing a motor generator and a battery, this regulator is equally well adapted for controlling prime mover dynamo plants in which the dynamo 105 electric machine functions merely as a dynamo and no battery is employed. Where the regulator is used in such a system its operation is substantially identical with its functions when a battery is employed, but its use 110 without a battery requires that it have an additional function which will now be described. Where a motor or similar device comprises a load, it may be found desirable 115 to start and stop it at frequent intervals and yet not cause a stopping of the gas engine and dynamo, as would be the case should the entire load be taken off of the dynamo, and the armature 21 permitted to rotate counter-clockwise its entire distance in which it locks 120 up the contact spring 53 out of engagement with contacts 52 and 56, causing a breaking of the ignition circuit and the stopping of the gasoline engine. In order to prevent the armature 21 from having its extreme movement, the handle 35, after the engine is started, is moved so that its pointer is opposite the index point "running without battery." 125 In this position the lever 33 is so disposed that it rests the counter-clockwise move- 130

ment of the arm 32 and shaft 22 at such a point that a small amount of fuel is fed the gas engine to keep it in operation and prevents the arm 40 from moving the contact 5 spring 53 out of engagement with contacts 52 and 56. If, with the engine running and the handle 35 in the position just mentioned, it is desired to stop the set, the said arm is moved so that its pointer is opposite the index point "stop automatic," in which position the lever 33 will be out of the path of movement of the arm 32 so that when the load is taken off of the generator this arm may move counter-clockwise to its extreme 15 position, in which the ignition circuit for the engine is broken, as previously described.

What is claimed is:

1. In combination, an internal combustion engine, a dynamo electric machine operated thereby, an output circuit supplied with electrical energy by the dynamo electric machine, an electromagnetic device to regulate the speed of the engine and to open the load circuit and the ignition circuit of the 25 engine in response to the variations in the electrical condition of the load circuit.

2. In combination, an internal combustion engine, a dynamo electric machine driven thereby, an output circuit supplied with 30 energy by the dynamo electric machine and an electromagnetic device to control the throttle valve of the engine and to open and close the ignition circuit thereof.

3. In combination, an internal combustion machine having an ignition circuit, a dynamo electric machine operated thereby, an output circuit supplied with energy by the dynamo electric machine, means to regulate the speed of the engine and to open the 40 load circuit and the ignition circuit, locking means to maintain these circuits open, an electromagnetic to normally control the operation of the first mentioned means and manually operated means whereby the operation 45 of the first mentioned means may be controlled and the locking means released.

4. In a system of the class described, an output circuit, a prime mover having an ignition circuit, a generator driven by the 50 prime mover to supply energy to the output circuit, and an electromagnetic device to control the speed of the prime mover in accordance with any variation in the electrical condition of the output circuit and to control the 55 ignition circuit of the prime mover.

5. In a system of the class described, an output circuit, a prime mover having an ignition circuit, a generator driven by the prime mover to supply energy to the output

circuit, and an electromagnetic device responsive to variations in load of the output circuit to regulate the speed and duration of operation of the prime mover in accordance with the variations in load of the output circuit, said device being provided with means for simultaneously opening the output circuit and the ignition circuit of the prime mover.

6. In a system of the class described, an output circuit, a prime mover having an ignition circuit, a battery bridged across the output circuit, a generator driven by the prime mover to supply energy to the output circuit and to charge the battery, and an electromagnetic device connected between the generator and battery responsive to variation in load of the output circuit to control the speed of operation of the prime mover, said device being provided with means to disconnect the generator from the output circuit and to open the ignition circuit under no-load condition when the battery is completely charged.

7. In a system of the class described, an output circuit, a prime mover having an ignition circuit, a battery bridged across the output circuit, a generator driven by the prime mover to supply energy to the output circuit and to charge the battery and an electromagnetic device comprising a series winding, a shunt winding, an armature therefor, a lever system operable upon movement of the armature to control the speed of the prime mover in accordance with the energy consumed in the output circuit, and a second lever system operable to open the output circuit upon reversal of the direction of current flowing in the series winding.

8. In a system of the class described, an output circuit, a prime mover having an ignition circuit, a generator driven by the prime mover to supply energy to the output circuit and an electromagnetic device having series and shunt windings, an armature therefor, a lever under the control of the armature to regulate the speed of the prime mover, a second lever under the control of the armature adapted to disengage the contacts in the ignition circuit of the prime mover, a latch for locking the contacts in the disengaged position, and a third lever cooperating with a manually set member to limit the speed regulation of said first lever.

In witness whereof, I hereunto subscribe my name this 21 day of March A. D., 1921.

HUGH M. STOLLER.
HUBERT A. PATTISON.
